UNITED STATES PATENT OFFICE.

STOTEN A. TAYLOR, OF SALEM, OHIO, ASSIGNOR TO THE SILVER MANUFACTURING COMPANY,
OF SALEM, OHIO, A CORPORATION OF OHIO.

HUB-BORING MACHINE.

No. 922,358.

Specification of Letters Patent.

Patented May 18, 1909.

Application filed March 11, 1907. Serial No. 361,808.

To all whom it may concern:

Be it known that I, STOTEN A. TAYLOR, a citizen of the United States, residing at Salem, in the county of Columbiana and State of Ohio, have invented certain new and useful Improvements in Hub-Boring Machines; and I do hereby declare that the following is a full, clear, and exact description of the same, reference being had to the annexed 10 drawing, making a part of this specification, and to the numerals of reference marked thereon, in which—

Figure 1 is a partial longitudinal vertical section of the machine showing the hub of a 15 wheel properly connected and in position to be reamed. Fig. 2 is a section on line 2—2, Fig. 4. Fig. 3 is a section taken on line 3—3, Fig. 4. Fig. 4 is a top view. Fig. 5 is an end view looking toward the left hand end of 20 Fig. 4. Fig. 6 is a perspective view of the mandrel casing, its clamp also showing the mandrel receded, also showing the mandrel moving clamp. Fig. 7 is a view showing the mandrel moving clamp open and the mandrel 25 moved forward. Fig. 8 is a view showing the sliding collar and the clamp holding head in proper relation with reference to the mandrel showing the clamp removed. Fig. 9 is a detached view of the clamp showing the 30 same open and in position to release the mandrel. Fig. 10 is a vertical section showing a portion of the housing also showing the sliding collar and the clamp properly located on the mandrel and the mandrel in proper 35 relationship with reference to the housing collar and clamp.

The present invention has relation to hub boring machines and it consists in the different parts and combination of parts hereinabove described and particularly pointed out in the claims.

Similar numerals of reference indicate corresponding parts in all the figures of the drawing.

In the accompanying drawing, 1 represents the bed-plate which is formed of any desired size and is supported in proper elevation by means of the legs 2, which legs may be formed integral with the bed-plate or attached by the lug bolts 3 as shown in Fig. 1.

Upon the bed-plate 1 is located the sliding table 4, which sliding table is provided with the downward extending flange 5, which downward extending flange is located

through the slot 6. For the purpose of reducing the friction as between the bed-plate 1 and the sliding table 4 the top or upper face of the bed-plate is provided with the ribs 7 and the flange 8, upon which ribs and flange the sliding table rests. At one side of 60 the bed-plate is located the downward extending flange 9 in which flange is journaled the screw 10, said screw being provided with the hand wheel 11, the screw is located through a screw threaded aperture formed in the flange 65 5, and by rotating the screw 10 the table 4 will be moved upon the bed plate, the movement of the table being in opposite directions when the screw threaded shaft is rotated in opposite directions; that is to say by 70 rotating the screw 10 in one direction the table 4 will be moved, say to the right, reference being had to Fig. 5 and when moved in the opposite direction will move to the left, reference being had to Fig. 5, by which arrangement the table 4 can be brought into proper adjustment for the purpose hereinabove described.

Upon the table 4 is pivotally mounted the mandrel housing 12, by means of the pin 13, 80 which pin is located in the aperture 14. The mandrel housing 12 is provided with the flanges 15, which flanges are provided with the slots 16, through which slots the clamping bolts 17 are passed, said clamping bolts 85 extending through the flanges, and into screw threaded apertures formed in the table 4, this feature being best illustrated in Fig. 3.

For the purpose of holding the housing 12 90 together with the different parts carried thereby in fixed position upon the table 4, after said housing together with the different parts carried thereby has been brought into proper adjustment, the clamp 18 is provided, 95 which clamp is provided with the screw 19, said screw being for the purpose of properly binding by means of the clamp 18, the housing 12, the table 4 and the bed plate 1 together, so there can be no relative movement as between said parts, after the housing 12 together with the different parts carried thereby has been placed in proper adjustment.

To the bed-plate 1 are attached the arms 105 20, which arms support and carry the ring 21, which ring is for the purpose of holding the relatively rotatable and intermediate

ring 22, which ring 22 is provided with the flange 23, which flange abuts against the ring 21. To the ring 21 is attached the ring 24, which ring abuts against the ring 22, by which arrangement the ring 22 is held in proper position with reference to the ring 21. It will thus be seen that the rings 22 and 24 are fixed with relation to each other but independent of the ring 21 and the ring 25 now to be described, in their movements. Upon the ring 22 is rotatably mounted the ring 25, which ring is provided with screw threads upon one of its faces, which screw threads mesh with the hub clamping bars 26, said hub clamping bars being slidably mounted in the brackets 27, which brackets are connected to the ring 22, by means of the clamping bolts 28 or their equivalents. When it is desired to clamp the hub the ring 25 is rotated independent of the ring 22 which rotation moves the clamping bars 26 endwise and when the ring 25 is moved in one direction it moves the bars 26 toward a common center, by which arrangement the hub 29 is properly centered and clamped.

It will be understood that the bars 26 must be provided with curved or segmental flanges 30, upon one of their faces so that said curved or segmental flanges will mesh with the screw threads formed upon the face of the ring 25.

For the purpose of providing means for snugly clamping the hub 29 the ring 25 may be provided with the apertures 31 in which apertures may be inserted the end of a bar to provide a suitable lever.

Upon the spokes of a wheel is seated the ring 32, and said ring snugly clamped to the spokes by means of the clamping screws 33. The outer ends of the brackets 27 are provided with the integral heads 34, which heads receive the screw threaded bars 35, receiving the adjusting nuts 36 and the binding nuts 37. The screw threaded bars 35 are for the purpose of adjusting the ring 21 together with all the parts carried by said ring into true parallel position with reference to the ring 32.

It will be understood that the boxings that are seated in the hub vary as to their taper, and the aperture or bore of the hub must necessarily taper, so that the boxing will snugly fit in the hub and in order to provide for the various degrees of taper to correspond with the various degrees of taper of the boxes to be seated in the hub, it is necessary to provide a means for adjusting the angularity of the mandrel 38, which adjustment is made by pivotally attaching the housing 12, to the table 4.

To the mandrel 38 is attached the boring tool 39 which of course may be of any desired construction reference being had to the particular kind of work designed to be accomplished. In this particular instance the

tool shown is what might be termed a reamer, but for other purposes different tools may be attached.

The operation of the device or machine is substantially as follows after a wheel has been properly connected to the revolving ring 22, by means of the device above described the mandrel 38 is set at the angle desired, and held in fixed adjustment. The mandrel clamp consisting of the pivoted jaws 40 is placed in the position illustrated in Fig. 6, said jaws being provided with the semi-circular grooves 41, which semi-circular grooves receive the flange 42 as best illustrated in Fig. 10. The flange 42 being formed at the end of the housing 12. The clamp jaws 40 are provided with the lateral semi-circular flanges 43 over which flanges the sliding collar 44 is placed when it is desired to hold the clamp in position to move the mandrel endwise as hereinafter described. In some instances it is desirable to open the clamp jaws so as to release the mandrel and permit the same to be moved endwise independent of any reaming or boring action, and in order to provide for this partial opening of the jaws the flanges 43 are provided with the reduced portions 45 by which arrangement the jaws can be partially opened when the sliding collar 44 is moved a distance sufficient to allow said collar to cover only the reduced portions 45 of the flanges 43. For the purpose of providing a means for entirely removing the clamp jaws 40 for any purpose the sliding collar 44 is provided with the notch 46 and when said notch is brought into alignment with the screw 47 or its equivalent the collar can be slid a sufficient distance upon the housing 12 to clear the reduced portions 45 of the flanges 43. It will be understood that the collar 44 must be rotatably and slidably mounted upon the housing 12. After a hub has been properly connected and the mandrel set at the desired angle the hub is rotated, which rotates all of the rings and parts carried by the rings 21 and for the purpose of causing the clamp jaws 40 to rotate therewith the L shaped bar 48 is provided, which bar is located between the clamp jaws 40 as illustrated in Fig. 1 the L shaped bar 48 is attached to the ring 24. It will be understood that when the hub is rotated the mandrel 38 will be moved endwise thereby causing the cutting tool to move endwise with the mandrel, by which arrangement the entire length of the bore in the hub can be acted upon and the bore brought to the desired size to receive and hold the boxing to be placed therein. By moving the table 4 laterally upon the bed-plate together with the different parts carried by said table. The mandrel together with the cutting tool can be shifted to or from the axially center of the hub. For the purpose of preventing the mandrel 125

from rotating during the time the hub is rotated the non-screw threaded portion of the mandrel is provided with the way 49, in which way is seated the key 50.

Having fully described my invention, what I claim as new and desire to secure by Letters Patent, is—

1. In a hub boring machine, the combination of a bed plate, a sliding table mounted upon the bed plate, a mandrel housing carried by said table and pivotally mounted thereon, a fixed ring carried by said bed plate, a rotatable ring carried by said fixed ring, said ring having screw threads upon one of its faces, a ring provided with brackets, sliding bars carried by said ring said sliding bars provided with curved flanges, said curved flanges adapted to mesh with the screw threads upon the screw threaded ring, a ring adapted to be connected to the spokes of a vehicle wheel, and means for connecting said ring with the rotatable ring carried by the bed plate, a mandrel carried by the mandrel housing, and means for imparting longitudinal movement to the mandrel by the rotation of the ring carried by the fixed ring secured to the bed plate, substantially as and for the purpose specified.

2. In a hub boring machine, the combination of a bed-plate, a sliding table mounted thereon, a mandrel housing carried by the table and pivotally mounted, a fixed ring supported from the bed-plate at one end thereof and at right angles thereto, a rotatable ring carried by the fixed ring, a ring rotatably mounted upon said rotatable ring and having screw threads upon one of its faces, brackets extending from the first-named rotatable ring, sliding hub-clamping bars mounted in said brackets and having curved flanges meshing with the screw threads upon said screw threaded ring, a ring adapted to be connected to the spokes of the vehicle wheel, means connecting said ring with said brackets, a mandrel carried by the mandrel housing, and means for imparting longitudinal movement to the mandrel by the rotation of the ring provided with the screw threads.

In testimony that I claim the above, I have hereunto subscribed my name in the presence of two witnesses.

STOTEN A. TAYLOR.
